UNITED STATES PATENT OFFICE.

JOHN H. WILLIAMS, OF EAST CLEVELAND, OHIO.

SWITCH-BOX.

1,163,388.

Specification of Letters Patent.

Patented Dec. 7, 1915.

Application filed August 4, 1913. Serial No. 732,771.

To all whom it may concern:

Be it known that I, JOHN H. WILLIAMS, a citizen of the United States, and a resident of East Cleveland, county of Cuyahoga, and State of Ohio, have invented a new and useful Improvement in Switch-Boxes, of which the following is a specification, the principle of the invention being herein explained and the best mode in which 5 I have contemplated applying that principle, so as to distinguish it from other inventions.

The present invention consists in a switch box adapted to be inserted in a wall 15 for the purpose of receiving the switch mechanism for operating an electric light circuit.

My improved switch box is provided with some convenient and serviceable means for 20 the attachment of the box to the wall, such means giving greater ease and rapidity of installation.

To the accomplishment of these and related ends said invention then consists of 25 the means hereinafter fully described and particularly pointed out in the claims.

The annexed drawing and the following description set forth in detail certain mechanism embodying the invention, such disclosed means constituting, however, but one 30 of various mechanical forms in which the principle of the invention may be used.

Figure 1 shows in perspective a view of the present type of box, together with the 35 attaching means for securing the same in the wall; Fig. 2 is a similar view but showing my improved attaching plate in position for engagement with the laths; Fig. 3 is a similar view showing my attaching 40 plate in position for engagement with a board; and Fig. 4 is a section on the line 5—5, Fig. 3.

As will be seen in Fig. 1, the switch box 45 consists of a box 1, roughly rectangular in shape, open on one side and provided with partially stamped out portions 2 which leave apertures when removed for the reception of the electrical wires. The switch mechanism proper is not shown as it forms 50 no part of the present invention.

In my improved box I have provided a universal engagement and attachment plate 9 which is permanently and pivotally attached to the box by means of a rivet 10, 55 such plate being provided with rounded faces 11 on its extending arms 12, such faces

being adapted to engage with a single button 13 having a head 14 which extends over the arm and tends to retain the same in engagement with the button. The button is 60 so disposed on the top of the box that it limits the pivotal movement of the plate and retains the same either parallel with the face of the box but spaced therefrom as in Fig. 3, in the other position of the plate, 65 flush with the front of the box, or as in Fig. 2, in which position the device is adapted to be secured to a lath. Upon one side of the plate is an upstanding lug 15 provided with two apertures 16 for receiving suitable 70 screws or bolts for attaching the same to a board or lath and upon the opposite side of the plate is a second lug 17 also apertured to receive the screw which passes through the cover plate. It will be noticed that between the apertures in the larger lug is a third aperture 18 which is aligned with the central aperture in the oppositely disposed lug 15 and serves the same purpose when the plate is in the position shown in Fig. 2. 75 It will be noticed that the buttons 13 are placed at diagonally opposite corners on the top and bottom of the box, this arrangement providing a stop which will tend to secure the box in its proper position whether 80 the tendency to move comes from the right or the left. Another advantage secured by this arrangement is that either end of the box may be placed up-right as both ends are identical. The advantages of my improved 85 switch box are its simplicity and the fact that the attachment plate is permanently and pivotally secured to the box.

Other modes of applying the principle of my invention may be employed instead of 90 the one explained, change being made as regards the mechanism herein disclosed, provided the means stated by any of the following claims or the equivalent of such stated means be employed.

I therefore particularly point out and distinctly claim as my invention:—

1. The combination with a switch box, of a universal engaging plate pivotally attached thereto, an upstanding lug attached 105 to one side of said plate and provided with suitable apertures adapted to receive means for attaching said box in a wall, and another lug mounted on the other side of said plate, said lugs being provided with apertures, 110 aligned with the axis of said plate, either of such aligned apertures being adapted in one

position of said plate to receive suitable means for attaching a cover plate to said box.

2. The combination with a switch box, of
5 a universal engaging plate pivotally attached thereto, and a button mounted on said box in position to be engaged by said plate upon pivotal movement of the same to limit the pivotal movement of said plate,
10 whereby the latter is always stopped in one of two operative positions.

3. The combination with a switch box, of

a universal engaging plate pivotally mounted upon either end of said box, and a button mounted on either end of said box to 15 limit the pivotal movement of said plate, said two buttons being mounted upon diagonally opposite sides of the ends of said box.

Signed by me, this 2nd day of August, 1913.

JOHN H. WILLIAMS.
